UNITED STATES PATENT OFFICE

HENRY C. HEISER, OF FAIRVIEW VILLAGE, OHIO, ASSIGNOR TO THE ASTRUP COMPANY, OF CLEVELAND, OHIO, A CORPORATION OF OHIO

ADJUSTABLE AWNING ARM

Application filed February 5, 1931. Serial No. 513,543.

The invention relates to awning arms adapted to maintain the awning fabric of a roller awning for a store front and the like in open or extended position, the awning arms also being adapted to be folded up against the vertical wall of the store front when the awning is not in use, as when the awning fabric is wound up upon its roller.

More particularly, the invention relates to an adjustable type of awning arm which may be made in standard sizes under production methods, and which may be adjusted at the time the awning is erected so that the outer end of the awning arm may be located at a certain specified or predetermined place, regardless of the places at which it may be required to attach the brackets to a wall for mounting the arm thereon.

Thus, it is necessary that all awning and awning arm parts be located at a certain predetermined distance above a sidewalk so as to provide sufficient clearance thereunder to permit pedestrians to walk beneath the awning without the liability of injury by accidentally striking an awning part.

Moreover, store fronts which are to be shaded by an awning, differ in arrangement and dimensions from each other, and are not uniform in providing suitable places for attaching brackets on which awning arms may be mounted.

And finally, having due regard for the required clearance, it is most desirable to maintain the awning in extended position as low as possible in order that a maximum shading of the store front may be obtained, regardless of the location of the places at which the mounting brackets for the awning arm are attached to the front wall.

Accordingly, it is an object of the present invention to provide an awning arm which may be attached to or mounted on a vertical wall, within desired limits, substantially at any place above the ground level, the outer end of the awning arm being adapted to be located at a fixed predetermined distance above the ground level to obtain the necessary clearance for and

maximum shading by the awning when the same is in extended position.

It is a further object of the present invention to provide an awning arm comprising a lever system forming a so-called lazy tong type awning arm in which one member of the lever system is adjustable as to effective length, and flexible throughout a portion of its length so as to permit the same to be adjustably connected to one of the awning arm mounting brackets for varying the location of the outer end of the awning arm in extended position without varying, changing, or modifying the length of any of the other links of the lever system.

And finally, an object of the present invention is to provide means for adjusting a lazy tong type awning arm, which adjustment means will not prevent the awning arm from being folded in a compact manner against the vertical wall upon which the awning is mounted, when the awning is rolled up.

These and other objects may be attained by a construction, preferred embodiments of which are shown in the accompanying drawings, which may be stated in general terms as including a compound lever comprising a pair of links, a flexible member connected to one end of said lever, a wall bracket, and means for adjustably connecting the flexible member to the wall bracket for varying the effective length of the flexible member.

Two embodiments of the improved adjustable awning arm construction are shown in the accompanying drawings, in which

Figure 1 is a side elevation of one form of awning arm showing the same in full lines in extended position at the upper limit of its adjustment, in dot-dash lines in extended position at the lower limit of its adjustment, and in dot-dot-dash lines in folded or retracted positions;

Fig. 2 is a vertical section through one form of bracket on which the awning arm is adjustably mounted;

Fig. 3 is a view similar to Fig. 2, showing the bracket of Fig. 2 in an adjusted position;

Fig. 4 is a perspective view of the component parts of the bracket shown in Figs. 1, 2 and 3; and

Fig. 5 is a sectional view similar to Fig. 2, showing a modified form of bracket and flexible member.

Similar numerals refer to similar parts throughout the drawings.

A single improved adjustable awning arm generally indicated at 5 is shown in Fig. 1, it being understood that two or more are required to be used in connection with every roller awning installation.

An awning roller 6 is supported on suitable brackets 7, which are attached to the vertical wall indicated by the line 8 above that portion of the wall which is desired to be shaded by the awning. Suitable winding devices (not shown) are provided for the awning roller 6 for winding up or unwinding the awning fabric 9 upon the roller 6.

Brackets 10 and 11, for supporting each adjustable awning arm 5, are attached to the wall 8 at available places located below the roller 6.

The awning arm 5 preferably comprises a lever system composed of links forming an irregular lazy tong which includes an outwardly extending arm or link 12 which is secured at its outer end 13 to a rod 14 to which the outer edge of the awning fabric 9 is attached.

The link 15 formed of twin channel bars is pivoted at 16 to the link 12; and the compound lever formed by the twin channel bar link 17 and the short link 18 pivoted at 19 to the link 17, is likewise pivoted at its outer end to the inner end of the link 12, as shown at 20. A lever arm or link 21 is pivoted at its inner end to the wall bracket 11, extends outwardly and upwardly from the wall 8 and is pivoted at its outer end to the inner end of the link 15 as shown at 22. An intermediate portion of the link 17 is pivoted at 23 to an intermediate portion of the link 21.

As thus far described, the irregular lazy tong awning arm is of an old and well known type, and my invention is directed particularly to the means by which the end of the link 18 is adjustably attached to the wall bracket 10.

In the preferred form of my invention, shown in Figs. 1 to 4, inclusive, the wall bracket 10 includes a base plate 24 preferably attached to the wall 8 by screws 25. A pair of ears 26 provided with apertures 27 extend outwardly from the lower end of the base plate 24, and a pair of ears 28 provided with a plurality of sets of spaced apertures 29 extend outwardly from the upper end of the base plate 24. A second plate or chain engaging member 30 is pivotally mounted at its lower end on a shaft 31 journaled in

the apertures 27 of the ears 26. A pair of ears 32 provided with apertures 33 extend outwardly from the plate 30 intermediate the ends thereof.

A flexible member 34 composed of pivoted links 34' forming a link chain is pivotally connected at 35 to the inner end of the short link 18 of the compound lever. A detachable bolt 36 journaled in the apertures 33 connects the flexible member 34 to the plate 30 of the wall bracket 10 by selective engagement with a relieved recessed portion 37 of any one of the links 34', the flexible member 34 being located between the ears 32, and the selectively engaged link being also engaged at its relieved recessed portion 37' by the rib 36 formed on the outer surface of the plate 30 as well shown in Figs. 2 and 3.

Relative movement between the plates 24 and 30 is restricted by a bolt 38 which engages the upper end of the plate 30 and may be selectively journaled in any set of the plurality of sets of apertures 29 formed in the ears 28.

Referring to Fig. 1, the adjustable awning arm 5 is shown in full lines in extended position at the upper limit of its adjustment wherein the outer edge of the awning is located as indicated at B after having been unrolled from a folded position shown in dot-dash lines wherein the outer edge of the awning is located as indicated at A. The adjustable awning arm is likewise shown in Fig. 1 in dot-dash lines at a lower limit of adjustment wherein the location of the outer edge of the awning is indicated at B'.

In one physical embodiment of the structure shown in Fig. 1, the point B is approximately six and one-half feet outward from the point A and approximately two and one-half feet below the point A, while the point B' is located approximately six feet outward from and six feet below the point A.

It is understood that the point B or B' is the determining position for the awning since it must be located at a distance above a sidewalk so as to provide sufficient clearance thereunder to permit pedestrians to walk beneath the awning, and the brackets 7, 10 and 11 must be attached to the wall 8 at available places, after which the awning arm mounting may be adjusted as required.

It is clear that the adjustment of the position of the awning arm 5 between the upper and lower limits shown in Fig. 1, is determined by the effective length of the flexible member 34, which determines the location of the point 35 with relation to the wall 8.

The effective length of the flexible member 34 may be adjusted or varied by selectively engaging any one of the links 34' thereof by the bolt 36, and in one physical embodiment of the invention, an adjustment from one link to the next adjacent link will result

in a vertical adjustment of the outer edge of the awning, approximately three and one-half inches.

Adjustment for the effective length of the flexible member 34, intermediate a link to link adjustment, is effected by selectively engaging the bolt 38 in one or another of the sets of apertures 29, there being three possible adjustable positions, the inner and outer of which are shown, respectively, in Figs. 2 and 3. In one physical embodiment of the invention, an adjustment of the bolt 38 from one set of apertures to the next adjacent set of apertures results in a variation of one and one-quarter inches of the vertical position of the outer edge of the awning.

In the modified form of my invention shown in Fig. 5, the wall bracket 10a includes a base portion 24a preferably attached to the wall 8 by screws 25. A pair of ears 32a extend outwardly from the base plate portion 24a and are provided with apertures 33a in which a bolt 36a is removably journaled.

The flexible member 34a is pivotally connected at 35a to the inner end of the short link 18 of the compound lever. Adjustment of the effective length of the flexible member 34a is accomplished by adjusting the location of the collar 39 secured to the flexible member 34a and abutted against the bolt 36a and the ear 40 projecting from the outer surface of the base plate portion 24a.

Accordingly, the location of the outer end of an adjustable awning arm may be varied by shifting the position of the collar 39 on the flexible cable member 34a.

Of course it is understood, that when an adjustable awning arm involving the present invention has been installed, and the adjusted location of the various parts has been made, the surplus end of the flexible member 34 or 34a may be cut off, the arrangement being permanent once the various parts have been adjusted to the required positions.

I claim:

1. In an irregular lazy tong awning arm, a link, a link chain connected to one end of said link, a wall bracket including a base and a chain engaging member pivoted thereto, means for restricting the pivotal movement between said base and chain engaging member, and means for adjustably connecting said link chain to said chain engaging member.

2. In an irregular lazy tong awning arm, a link, a link chain connected to one end of said link, a wall bracket including a base, the base being provided with a plurality of sets of outwardly projecting ears, a chain engaging member pivoted to one of said sets of ears, means carried by the other set of ears for restricting the pivotal movement between said base and chain engaging member, and means for adjustably connecting

said link chain to said chain engaging member.

3. In an irregular lazy tong awning arm, a link, a link chain connected to one end of said link, a wall bracket including a base, the base being provided with a plurality of sets of outwardly projecting ears, a chain engaging member pivoted to one of said sets of ears, adjustable means carried by the other set of ears for restricting the pivotal movement between said base and chain engaging member, and means for adjustably connecting said link chain to said chain engaging member. 70

4. In an irregular lazy tong awning arm, a link, a link chain connected to one end of said link, a wall bracket, each of the link chain links being provided with a recessed portion, and means on the bracket for selective engagement with the recessed portions 80 of the links of said link chain. 85

5. In an irregular lazy tong awning arm, a link, a flexible cable connected to one end of said link, a wall bracket, a collar adjustably mounted on the cable, and means on the bracket engaging the collar and cable in 90 any adjusted position of the collar. 90

6. In an irregular lazy tong awning arm including a pair or cross bars, a wall bracket connected to one of said bars, said other bar comprising a compound lever having a pair of links, a flexible member connected to one end of said compound lever bar, a second wall bracket, and means for adjustably connecting the flexible member to the second wall bracket for varying the effective length 95 of the flexible member to vary the vertical location of the outer end of the awning arm when in extended position. 100

7. In an irregular lazy tong awning arm including a link, means for adjusting the vertical location of the outer end of the awning arm when in extended position including a flexible member connected to one end of said link, a wall bracket, and means for adjustably connecting the flexible member to the wall bracket for varying the effective length of the flexible member to vary the location of the awning arm when in extended position. 105

8. In an irregular lazy tong awning arm including a link, means for adjusting the vertical location of the outer end of the awning arm when in extended position including a flexible member connected to one 110 end of said link, a wall bracket, means for adjustably engaging the flexible member to the wall bracket, and means for adjusting the position of the engaging means to vary the location of the awning arm when in 115 extended position. 120

9. In an irregular lazy tong awning arm, a link, a link chain connected to one end of said link, a wall bracket including a base and a chain engaging member mounted on 130

the base for movement to adjusted positions, and means on the chain engaging member for selective engagement with the links of the link chain when the chain engaging member is in any adjusted position.

5 In testimony that I claim the above, I have hereunto subscribed my name.

HENRY C. HEISER.
